UNITED STATES PATENT OFFICE.

SERAPHIN V. DAVIN, OF WALLA WALLA, WASHINGTON.

DISK HARROW.

1,324,882.

Specification of Letters Patent. Patented Dec. 16, 1919.

Application filed April 3, 1918. Serial No. 226,388.

To all whom it may concern:

Be it known that I, SERAPHIN V. DAVIN, a citizen of the United States, residing at Walla Walla, in the county of Walla Walla 5 and State of Washington, have invented certain new and useful Improvements in Disk Harrows, of which the following is a specification.

This invention relates to disk harrows which have two or more sections of cutting disks and has for its object to combine a number of elements with an old device, in such a manner as to perfect the said device, that greater strength, rigidity, durability 15 and effectiveness is obtained.

In order that this invention may be better understood reference is had to the accompanying drawings in which:

Figure 1 is a plan view of the harrow; 20 Fig. 2 is a side elevation;

Fig. 3 is an enlarged rear elevation showing the adjuster with part of the beam in section;

Fig. 4 is a partial side elevation showing 25 the cleaner bar;

Fig. 5 is a plan view of the adjuster;

Fig. 6 is a side elevation of the supporting members;

Fig. 7 is a sectional view of one of the 30 pedestal bearings.

In the drawings, 11 represents the side-pieces of the frame, held together by the cross ties 12 and braced by the members 13, a single piece 14 ties the front and rear portions together and on this piece a seat 15 is suitably fastened.

On the under side of the side bars 11 of the frame and held at the proper distance therefrom by spacing sleeves 16 are guide 40 bars 17, and between the guide bars and the side bars of the frame are mounted beams 18; said beams being pivoted near one end and free to move in a horizontal plane about the axis of the pivot which consists of a bolt 45 19 and spacing sleeve 16. In addition to the above movement, one or both beams may be arranged to have a lateral movement, as will hereafter be explained.

Cleaner bars are provided consisting of 50 strips 20 placed parallel with the beams and supported by projecting pieces 21 which are bolted to the beams, these pieces being of a length sufficient to hold the strip below the guide bars so that free movement, with relation to the guide bars, may be had, and the cleaner bars proper 22 bolted to the strips

20 and extending downward at an angle and resting against the rearward side of the disk axle 23 and close to the cutting edge of the disks 24.

By means of the cleaner bars the disks are continually cleaned of mud or weeds and thus are more effective.

To the under side of the beams pedestal bearings 25, inverted, are attached, in which the disk shaft 26 is revolvably mounted. The pedestal or post of these bearings is hollow, 65 27, and serves as a reservoir for oil, ingress being through a hole 28 provided for that purpose in the beams and registering with 70 a corresponding hole 29 in the cast head of the pedestal, and egress being through a small hole 30 in the base which registers with a corresponding hole 31 in the bearing material. This bearing material consists of 75 wooden blocks 32 bored to receive the shaft 26 and of a length to project beyond the cap 33 of the box, the ends thereof acting as thrust bearings against the disks, thus the wear comes on the wood, which is most effective. The blocks 32 are split horizontally 80 that they may be readily placed on the shaft 26 and are held in place by the cap 33 and bolts 34.

On the base of the bearings are hooks 35 held in place by the above mentioned bolts (the hooks may be cast integral with the bearing if desired), the purpose of which will be presently explained.

On the front end of the frame and slightly 90 below its level is the draft bar 36 which is suitably supported by the bent piece 37 and the guide bars 17 extended and bent to receive the lower side of said draft bar. On the inner or rear side of this bar, and suitably attached thereto are hooks similar to, 95 and in line with, the above mentioned hooks 35 on the bearings 25.

By referring to Fig. 3 it will be noted that the disk shaft 26 is located considerably below the frame and as the pull is on the frame the beams 18 have a twisting tendency which would spring the guide bars 17.

To prevent this the hooks 35 are suitably attached to the rear of the draft bar 36, on 105 both the front and rear of the forward pedestal bearing and the front of the rearward pedestal bearing, and supporting members 38, which may consist of chain or other means, attached to said hooks. That horizontal adjustment of the disks may be accomplished conveniently the supporting 110

members 38 are arranged to be disconnected from the hooks 35, the proper adjustment is then made and the supporting members reconnected. Thus absolute rigidity of the 5 disks is maintained.

Any suitable draft device may be applied to the draft bar.

On top of the side bar 11 is located an adjuster 39 by means of which a lateral movement to the beams is obtained.

This adjuster swings with the beam 18 and upon its pivot and consists of a plate 40, operating lever 41 and adjusting bar 42. The plate is attached to the side bar 11 by 15 means of the aforementioned pivot and extends horizontally and in line with the beam. The plate is suitably provided with lugs 43 to which are pivotally attached the operating lever 41 and adjusting bar 42 respectively. The operating lever projects downward through a slot 44 in the plate and engages the beam through a slot 45 therein with which the tongue 46 of the operating lever registers. The operating lever being 25 held rigidly in the required position by means of the bolt 47, which passes through the operating lever and through the slot 48 in the adjusting bar, and the hand lever nut 49. Beam 18 is also slotted at 50 to provide 30 for the lateral movement.

It will now be seen that by moving the operating lever the beam, and with it the disks, are moved laterally and thus "tracking" is prevented, also that greater movement of the beams about the pivot may be obtained as when the disks are drawn apart at one end the other ends close toward each other they might otherwise have a tendency to rub, whereas a slight movement of the adjusting lever places the disks in the best operable position and prevents rubbing.

On the extreme outer end of the rearward disk axle is placed a disk 51 having a smaller diameter which acts as a marker and guide 35 for subsequent work.

The horizontal movement of the disk beams is obtained by means of the lever 52 and connecting rods 53; as this forms no part of my invention further explanation is deemed unnecessary.

With the above specification in mind it will now be noted that this disk harrow is

capable of lateral and horizontal adjustment and perfect rigidity is maintained at all times; that by preventing "tracking" more thorough work may be accomplished; by marking the rows as we go the work is more uniform and by perfect rigidity the harrow is made more lasting and the work is accomplished with less labor.

Having thus described my invention, I claim:

1. In a disk harrow, a frame, a forward beam pivotally attached at one end to the frame, a rearward beam pivotally and slidably attached at one end to the frame, pedestal bearings attached to said beams intermediate the ends thereof, shafts revolubly mounted in said bearings, and disks carried by the shafts.

2. In a disk harrow, a frame, a forward beam pivotally attached at one end to the frame, a rearward beam pivotally and slidably attached at one end to the frame, a laterally operating means pivotally mounted on the frame and engaging the said last mentioned beam, pedestal bearings attached to said beams, intermediate the ends thereof, shafts revolubly mounted in said bearings, and disks carried by the shafts.

3. In a disk harrow, a frame, a forward beam pivotally attached at one end to the frame, a rearward beam pivotally and slidably attached at one end to the frame, pedestal bearings attached to said beams, hooks carried by said bearings, shafts revolubly mounted in said bearings, disks carried by the shafts, a draft bar attached to the frame, adjustable supporting members attached to the draft bar and engaging hooks on the forward bearings, and adjustable supporting members engaging hooks on the forward bearings and extending to and engaging hooks of the rearward bearings.

4. In a disk harrow, a frame, a forward beam pivotally attached at one end to the frame, a rearward beam pivotally and slidably attached at one end to the frame, and disk revolubly supported by the beams, substantially as described.

In testimony whereof I have affixed my signature.

SERAPHIN V. DAVIN.
